UNITED STATES PATENT OFFICE.

ALEXANDER WINTON, OF LAKEWOOD, OHIO, ASSIGNOR TO THE WINTON GAS ENGINE & MFG. CO., OF CLEVELAND, OHIO, A CORPORATION OF OHIO.

FUEL-INLET-VALVE MECHANISM.

1,254,872.

Specification of Letters Patent. Patented Jan. 29, 1918.

Application filed December 12, 1914. Serial No. 878,971.

To all whom it may concern:

Be it known that I, ALEXANDER WINTON, a citizen of the United States, residing at Lakewood, in the county of Cuyahoga and State of Ohio, have invented certain new and useful Improvements in Fuel-Inlet-Valve Mechanism, of which the following is a specification.

This invention relates to improvements in internal combustion motors and particularly to fuel inlet valve mechanism therefor.

More specifically the invention relates to fuel valve mechanism for internal combustion motors, and it comprises a valve structure including fuel and air mingling means, a plurality of mixing cups arranged to thoroughly mix and break up the mingled air and fuel, and a discharge valve for discharging the mixture into the cylinder.

The invention may be further briefly summarized as consisting in the construction and combination of parts, hereinafter set forth in the following description, drawings and claims.

Referring to the drawings, Figure 1 is a view of an engine provided with my improved valve; Fig. 2 is a vertical sectional view of the valve structure; Fig. 3 is a top plan view of the valve structure with the stuffing box and spring mechanism removed; Fig. 4 is a top plan view of the fuel and air mixing device; Fig. 5 is a vertical section through the same; Fig. 6 is a top plan view of one of the mixing cups; and Fig. 7 is a sectional view through one of these cups.

In carrying out the invention any preferred form and construction of engine may be employed, provided they possess the necessary characteristics, but I have shown one arrangement which is effective, and in such embodiment 1 represents the crank case of an explosive engine provided with a suitable cylinder 2 receiving a piston 3. This piston is connected in a manner not shown, by a connecting rod, with the crank shaft which is in the crank case 1, the details of these parts being unimportant in so far as the invention is concerned. Mounted upon the crank case is a suitable air pump 4 which is adapted to supply air under high compression to a supply pipe 5. A fuel pump 6 is also provided on the crank case and it receives fuel through a suitable pipe 7 and supplies it under high pressure to a pipe 8.

The cylinder 2 is provided with a suitable head 9 having a main air inlet valve structure 10 and an exhaust valve 11, these valves being of the tappet valve type and being seated in the usual manner. They are operated by mechanism, not shown, in the usual manner. The foregoing features are common to devices of this character, and are only set forth for the purpose of forming a foundation for any combination claims which may appear.

The fuel and air mixing valve structure comprises a cylindrical casing 12 adapted to project through the cylinder head to a point near the combustion chamber. This casing is provided with diametrically disposed extensions 13 each having an opening 14 for a securing bolt. Integral with one of these extensions are suitable connections 15 and 16, the former having an opening 17 therein for receiving the air pipe 5, the latter having an opening 18 for receiving the fuel supply pipe 8. The opening 17 communicates with a part 19 formed in the casing and extending to a central longitudinally disposed opening 20 extending through the casing. The opening 18 in the connection 16 is connected by a port 21 with a longitudinally disposed fuel port 22 extending to a point near the bottom of the casing, and there communicating with a lateral port 23 leading to a mingling chamber 24 formed by enlarging the opening 20 in the casing. At a point corresponding to the connections 15 and 16, the casing is reduced internally at 25 for guiding the valve stem, as will later appear, and above this point the casing is provided with a stuffing box extension 26 externally threaded and having an enlarged opening 27 for receiving packing 28, which is engaged by a gland 29 held in place by a gland nut 30 provided with a flange 31 receiving the thrust of a spring 32. The lower end of the casing is enlarged at 33 over the chamber 24 to receive the threaded shank 35 of a plug 36. This plug is bored out to form a mixing chamber 37 and is again reduced by a tapering portion 38 to a discharge opening 39 having a valve seat 40 at the outer edge. Coöoperating with this valve seat is a valve 41 carried by a valve shank 42 preferably integral with the valve stem 43 which extends up through the entire valve structure, through the guiding portion 25,

through the packing 28 and out at the top where it has an annular groove 48 receiving a split collar 44 adapted to engage in a tapered opening 45 in a spring washer 46 adapted to receive the upper thrust of the spring 32. This structure is common in devices of this sort.

Within the mixing chamber 37 in the plug 36, the stem 43 is provided with a plurality 10 of mixing cups comprising a cylindrical portion 47 and a bottom flange 48 which is provided with a plurality of minute openings 49 and a central opening 50 for receiving the stem 43. There is a plurality of 15 these cups, as stated, and they are sufficient in height when arranged one upon the other to occupy the mixing chamber 47 and they are held in place by a mingling block 51 which is provided with a central opening 52 20 larger than the valve stem 43 and corresponding in bore to the bore of the opening 20, thus permitting the continuance of the flow of air through the opening 20 about the valve stem. This block is provided peripherally with an annular groove 53 at a point 25 in alignment with the port 23, and this recess communicates by diagonally disposed inwardly extending ports 54 with the central opening in the block, so that the fuel 30 which enters through the ports 22 and 23 passes into the annular groove 53 and is thence distributed through the diagonal ports 54 in a series of streams to the air, the mingled fuel and air then passing from 35 one mixing cup to the other and finally entering the chamber 39, from whence at the proper time it is discharged through the valve into the cylinder.

Having described my invention, I claim—

1. A fuel and air mixing valve structure comprising a casing having a discharge, a longitudinally disposed opening therein forming an air supply port, a fuel supply port extending from the outside of the casing to a point near the discharge end of said casing and communicating with the air supply port, a fuel and air mingling block arranged in the air supply port and communicating therewith, and also communicating with the fuel supply, a discharge plug arranged in the end of said casing adapted to hold said mingling block in place and provided with a plurality of mixing cups arranged in said plug and each 55 having a plurality of minute openings in the

bottom, a discharge valve arranged in said plug, and means for actuating said valve.

2. A fuel and air mixing valve structure comprising a casing having a discharge, a longitudinally disposed opening therein 60 forming an air supply port, a fuel supply port extending from the outside of the casing to a point near the discharge end of said casing and communicating with the air supply port, a fuel and air mingling block arranged in the air supply port and communicating therewith and also communicating with the fuel supply, a discharge plug arranged in the end of said casing adapted to hold said mingling block in place and provided with a plurality of mixing cups arranged in said plug and each having a plurality of minute openings in the bottom, a discharge valve arranged in said plug, and a valve stem extending through the mixing 75 cups, through the mingling block and the casing for actuating said valve.

3. A fuel and air mixing valve structure comprising a casing having a central longitudinally disposed opening for the passage 80 of air for a valve stem and terminating at the lower end in a mingling chamber, a fuel supply opening extending longitudinally through the casing and communicating with the mingling chamber, a mingling 85 block arranged in the mingling chamber and provided with an annular recess for receiving fuel from the fuel supply port and diagonally disposed openings for supplying fuel to the centrally disposed opening in said block, a plug in the lower end of said casing and having a mixing chamber and a discharge opening, a plurality of mixing cups arranged in said mixing chamber, and each comprising a cylindrical portion and a bottom flange provided with minute openings and a centrally disposed opening, a discharge valve for controlling the discharge through the centrally disposed opening in said mixing cups, through the opening in 100 said mingling block, through the air supply opening, and out through the top of the casing.

In testimony whereof I affix my signature in presence of two witnesses as follows.

ALEXANDER WINTON.
